WASHING BAG

Edna E. Lyon, Detroit, Mich.

Application June 2, 1949, Serial No. 96,773

5 Claims. (Cl. 150—1)

1

My invention relates to open-mesh containers or bags of net-woven type in which the various parts of the bag structure are constructed and arranged in a novel manner in order to secure maximum strength and wearing quality and to greatly facilitate the washing of articles which may be enclosed therein.

In recent years there has been a large increase in the number of automatic washing machines, not only in the hands of private owners but also in "laundrettes" or self-service laundries and other places where the members of the public are permitted to carry out the washing operations in rented automatic washing machines. One of the difficulties of utilizing such equipment arises from the fact that many articles which are normally present in a household wash are likely to be torn or otherwise damaged. For example, fastening means, such as belts, buckles, straps, buttons and so forth, are more or less frequently damaged or detached. Moreover, many garments are required to be washed which are of such delicate structure or fragile materials as to require protection during the washing operation such, for example, as curtains, silk or lace garments, sheer handkerchiefs, nylon stockings, and runners of various types which are likely to become entwined or twisted among other articles being washed or in the paddles or other equipment of the washing machine itself.

The primary object of my invention is to so design an open-mesh bag for use in automatic washing machines that such articles as those above-mentioned may be enclosed and loosely retained therein while being subjected to adequate washing and, at the same time, protected against such damage as might otherwise occur.

My invention contemplates such a bag structure of relatively light weight, constructed of such material as cotton mesh or nylon mesh in which the maximum linear dimension of any openings therethrough may never exceed $\frac{3}{2}$ to $\frac{1}{16}$ of an inch and in which at least $\frac{1}{3}$ and preferably $\frac{1}{2}$ or more of the surface of the material may be open to facilitate the flow of the water therethrough and accommodate a complete and thorough washing of such goods as may be enclosed within the bag. The maximum size of the opening should be such as to permit free flow of the water through the bag and, at the same time, small enough as to confine such portions of articles enclosed therein as may be likely to project therethrough.

Still another object of my invention is to so design such a bag as to permit practically the en-

2

tire surface thereof to accommodate free flow of the water therethrough and so designed that a minimum of waste will occur in the manufacturing process.

5 My novel bag structure contemplates an arrangement generally rectangular in form which may be constructed by one simple folding operation, either lengthwise or crosswise of the bag, and stitching around the edges to be joined of such form as will fold in said open edges at the same time they are secured together by some form of resilient stitch, such as the so-called overcast or other similar stitch, which will protect the sewed edges and at the same time insure the proper functioning of the bag as above set forth.

10 An important novel feature of my bag is the manner in which a portion only of one side or edge of the bag is provided with an opening of such character as to prevent the egress therefrom of articles once enclosed and, at the same time, leave substantially the whole area of the bag available as washing surface through which the water may readily pass.

15 Another object of my invention is to design such a bag as that described of generally rectangular form, having at least three edges completely closed and the fourth edge closed adjacent both corners and open therebetween, with a series of fastening means along said open portion which may readily be secured or released and of such character as will not interfere with the washing operation in automatic machines.

20 In the drawings, Figure 1 is a perspective side elevation with the edges of the opening laid back to disclose the securing means.

25 Figure 2 is an enlarged view of a portion of the bag at the open end, showing in greater detail the open mesh structure and the construction at the mouth end of the bag.

30 Figure 3 is a fragmentary view comparable to Figure 2, illustrating a "zipper"-type fastening for the mouth of the bag.

35 Describing my novel structure in detail, it may be noted that the bag generally indicated at 2 is of rectangular form with the opening or mouth 4 at the top thereof. As illustrated, said bag may be formed of a single piece of material folded upon itself at the bottom edge 6 and stitched or overcast at the opposite sides thereof as at 8 and 10. The top corners, as at 12 and 14, are lock-stitched inwardly along the upper edge thereof so that they will be closed and the mouth 4 may consist of an opening extending from $\frac{1}{2}$ to $\frac{2}{3}$ of the distance across the top or open edge of the

bag. Along the inner and oppositely facing edges of the mouth 4 may be firmly secured as by a lock-stitch as at 16 and 18 (Figure 2) a tape 20 formed of closely woven material, the stitching at the ends of said tape carrying into the portions 12 and 14 at the opposite sides of the mouth 4 and the ends of said tapes being secured by the stitching at 12 and 14. The tape 20 at one side of the mouth may have a series of snapper buttons 22 evenly spaced therealong, and the opposite tape 20 may likewise have equally spaced therealong snapper eyes 24. Both portions of the snappers 22 and 24 are so enclosed within the tapes 20 that the only projecting parts are the button portions 22 which snap into the eyes 24. No other metal is exposed and these buttons, of course, are also enclosed when the bag has been shut and is ready to place in the washing machine. By this means, no metal whatsoever is exposed.

The open-mesh character of the material of which the bag is formed is well illustrated at 26 in which it may be seen that I have illustrated a material which is relatively loosely woven in order to accommodate the free flow of the water therethrough as above described. Although I have illustrated a weave in which the warp and the woof each consists of a plurality of threads relatively close together and separated from the next similar group by a relatively wide space, nevertheless, it will be understood that varying forms of warp and woof arrangements may be permitted, providing sufficient open space is afforded to accomplish the purposes above set forth.

An important feature of my novel bag is the construction and arrangement of the mouth at a point intermediate the corners along one side or one end. It will readily be understood, of course, that the material of which the bag is constructed may be folded lengthwise or crosswise of the bag. If it is folded lengthwise, as illustrated in Figure 1, stitching will be necessary at both sides and along the opposite edges of the top. If it is folded crosswise, stitching will be required along the bottom, along one side and at opposite edges of the top. It will be readily apparent to those skilled in the art that economy of certain width material may be secured by folding in one direction and of a different width of material may be had by folding in the other direction, depending upon the size or sizes of the bags desired to be formed and the widths of the various types of material being used.

In any case, however, an important feature of my arrangement is having the mouth of the bag placed intermediately along one side or end with closed corners at opposite edges of the mouth. This is important because it permits the opening to be placed most conveniently for insertion or removal of the articles which are to be enclosed while, at the same time, permitting the corners to be securely sewed and preventing the egress therefrom of small articles, as might otherwise take place if the corners were not so closed. At the same time, the mouth or opening of my novel bag is so constructed as to permit a series of fastenings to be affixed along the edges thereof with maximum economy of space so that substantially the entire surface of the bag is available for free flowing of the washing medium therethrough. Economic advantages are obtained by having the mouth extended along only one portion of the edge of the bag. This not only reduces the number of fas-

teners required and thus lowers the cost but it also permits a more secure structure of the bag itself at opposite sides of the mouth while presenting an extremely neat and convenient arrangement. If the corners were not fully closed at opposite sides of the mouth, small ends, such as belts or sashes, would work out at the edges of the bag. This mouth structure affords an adequate opening which may be conveniently opened or closed, while at the same time it avoids "bunching," gathering or folding over at one end of the bag as is commonly done with pins or ties. Such bunching reduces capacity and is very objectionable because maximum surface needs to be available for the water to wash through.

The fastening means illustrated in Figures 1 and 2 are snapper-type fasteners, and these are set relatively close together. It will be understood, of course, that a "zipper"-type fastener might be used to close the opening, as illustrated in the fragmentary view of Figure 3, generally similar to the view of Figure 2 but wherein the tapes 28 and 30 at opposite sides of the opening have co-acting "zipper" means 32 fixed therealong for closing the opening. As in the modification of Figures 1 and 2, the fastening means are secured on the inner faces of the sides of the mouth and spaced from the extreme edges thereof so that the metal is not exposed when the mouth is closed.

I claim:

1. A washing bag of flexible fabric of interlaced strands defining mesh material stitched along meeting edges to close entirely three margins and a fourth margin adjacent opposite extremities thereof, said fourth margin being open intermediate said extremities to form a mouth, fastening means comprising closely woven tape with snap closing means stitched entirely around said mouth and into each adjacent extremity of said fourth margin and adapted to close said mouth and be retained therewithin, said mouth extending along at least one half the length of said fourth margin, said fabric having openings in which the maximum linear dimension thereof does not exceed from three thirty-seconds to three sixteenths of an inch and said openings comprising from one third to three fourths of the surface of said bag, the structure and arrangement of said mouth and closing means affording maximum washing capacity of said bag without bunching, gathering and crowding at the mouth end thereof.

2. A washing bag formed of net material folded upon itself to define one side and stitched around the meeting edges thereof to close entirely three sides and stitched along portions of the fourth side at opposite extremities thereof, an opening formed between said extremities with closely woven tape means securely stitched along opposite faces of said opening and into said extremities, the respective tape means at opposite faces of said opening having complementary fastening means therealong adapted to be secured to each other to close said opening and conceal said fastening means, said fastening means and said opening being so constructed and arranged as to avoid gathering and bunching of said net material and affording maximum capacity and washing area, said net material having open spaces therein not exceeding three thirty-seconds to three sixteenths of an inch and comprising not to exceed one third to three fourths of the total surface of said bag.

3. In a washing bag, a structure formed of

flexible fabric of interlaced strands, said fabric being folded over itself to form one side and stitched around the meeting edges thereof to form three sides entirely closed and a fourth side closed along portions at opposite ends thereof and open intermediate said closed portions to define a mouth for insertion or removal of articles designed to be washed therein, said stitched portions at opposite sides of said mouth forming closed corners of said bag with the adjacent sides thereof to prevent escape of small articles enclosed therewith at the mouth end of said bag, the warp and woof arrangement of said fabric being so formed that the openings therethrough comprise at least one third but not more than three fourths of the surface thereof and each of said openings having a maximum linear dimension not to exceed three thirty-seconds to three sixteenths of an inch, and closely woven tape carrying snap closing means stitched entirely around said mouth and into said adjacent portions and retained within said bag when closed.

4. In a washing bag, a structure comprising mesh material stitched around the meeting edges thereof to form three sides entirely closed and a fourth side closed at opposite ends thereof and open intermediate said ends to define a mouth, and closely woven tape with fastening means spaced therealong stitched on the opposite sides of said mouth and into said closed ends, said mouth and fastening means being so constructed and arranged as to afford maximum washing capacity of said bag without bunching or gathering any portion thereof, said mesh material having openings with maximum linear dimensions not to exceed three thirty-seconds to three sixteenths of an inch and comprising at least one third the total surface of said bag.

5. In a washing bag, a structure comprising mesh material stitched around the meeting edges

thereof to form three sides entirely closed and the fourth side closed at opposite ends thereof and open intermediate said ends to define a mouth for insertion or removal of articles designed to be washed therein, closing means for said mouth so constructed and arranged as to afford maximum capacity and washing area at the mouth end of said bag without gathering or bunching said mesh material, said mouth comprising closely woven tape stitched around the margins thereof and into said opposite ends of said fourth side, said tape carrying spaced fastening means to close said mouth and retain said tape and fastening means within said mouth when closed, said mesh material affording full washing surface with openings therein having maximum linear dimensions not to exceed three thirty-seconds to three sixteenths of an inch and comprising at least one third of the total surface of said bag.
